Primary Examiner — Catherine S Posthauer*Assistant Examiner* — Joan E. Diehl(74) *Attorney, Agent, or Firm* — Eckert Seamans Cherin & Mellott, LLC(57) **CLAIM**

The ornamental design for a metal container as shown and described.

DESCRIPTION

FIG. 1 is a side elevation view of a metal container, showing my new design;

FIG. 2 is a bottom plan view thereof;

FIG. 3 is a top plan view thereof; and,

FIG. 4 is a rotated bottom perspective view thereof. Stippling shown in the drawings illustrates a contrast in surface texture which forms part of the claimed design. Broken lines shown are for the purpose of illustrating both boundaries of the claim and parts of the article. None of the broken lines form part of the claimed design.
